CLOTHESPIN

Howard E. Ott, Glendale, Calif.

Application January 14, 1953, Serial No. 331,129

1 Claim. (Cl. 24—139)

1

This invention relates to new and useful improvements in wire clothespins.

The invention is more particularly concerned with wire clothespins of the so-called line-attached type whereby the pins remain on the line when not in use and are in fact irremovable from the line except by threading same over one end of the line after disconnection of such end.

A primary object of the invention is to provide a wire clothespin of the above noted general character which is of generally circular form and embodies substantially diametrically opposed yieldable clothes clamping portions whereby adjacent edges of two pieces of laundry may be effectively clamped to a line in the absence of lapping of such edges.

A further object of the invention is to provide a wire clothespin which is capable of being manipulated from a suspended inoperative position on a clothesline into operative laundry gripping relation with a minimum expenditure of time and effort.

A still further object of the invention is to provide a wire clothespin which is of maximum simplicity in construction, durable in use, and which is capable of manufacture at relatively low cost.

Other objects and advantages of the invention will become apparent in the course of the following detailed description, taken in connection with the accompanying drawing, wherein:

Fig. 1 is a side elevational view of the improved clothespin in accordance with a preferred structural embodiment thereof.

Fig. 2 is an edge view as observed from the right of Fig. 1.

Fig. 3 is a top plan view.

Fig. 4 is a perspective view showing the improved clothespin in operative position on a portion of a clothesline.

Fig. 5 is an elevational view on a reduced scale showing a fragmentary length of a clothesline, two of the pins in operative association with fragmentary portions of two pieces of laundry and a third pin in inoperative suspended position on the line.

Referring now in detail to the drawing, the improved clothespin is designated in its entirety as 10. The pin 10 is formed from a single length of wire having inherent resiliency transversely of its axis. The single length of wire is bent intermediate its ends into a substantially circular body portion 11. The two strands are then twisted together at spaced points 12 and 13 with relatively short lengths of the strands juxtaposed axially

2

of the body portion 11 and intermediate the twists 12 and 13 as indicated at 14.

The end portions 15 and 16 of the wire are then bent into substantial conformity with the generally circular body portion 11 and as is apparent from Figs. 1, 3 and 4 the twists 12 and 13 are such that the arcuate end portions 15 and 16 are disposed at axially opposite sides of the body portion 11 and in substantial conformity therewith.

The portions 15 and 16 normally substantially engage the body portion 11 and provide therewith a pair of line and laundry gripping jaws 17 and 18. The portions 15 and 16 provide spring arms and they preferably extend substantially beyond the center of the body portion 11 from the respective twists 12 and 13 and in order to facilitate admission of the line and laundry suspended therefrom within the jaws 17 and 18. The ends of the arms 15 and 16 are turned outwardly in opposite directions from the plane of the body portion 11 into the general form of eyes 19 and 20 respectively as is more clearly indicated in Fig. 2.

As is indicated in Fig. 5 pieces of laundry indicated fragmentally at 1 and 1' are shown suspended from a suitable line L. One of the improved pins 10 is in operative position on the line and in gripping relation with the left edge of the piece of laundry 1 and wherein such edge is gripped within the jaw 18 provided by the body portion 11 and associated spring arm 16.

The other clothespin 10 shown in this view is also in operative position on the line L and the opposite edge of laundry piece 1 is gripped within jaw 17 provided by the body portion 11 and associated spring arm 15, while the edge of the laundry piece 1' is gripped within jaw 17 provided by the body portion 11 and associated spring arm 16.

Thus it will be apparent that the improved clothespin in accordance with the present invention is adapted to secure one edge of a piece of laundry or the adjacent edges of two pieces of laundry without lapping such edges whereby the laundry will dry more uniformly throughout.

It is to be particularly observed that the improved clothespin is of maximum simplicity in construction and since it is constructed of wire preferably of a rustproof nature it will last for an indefinite period of time. Furthermore the pins remain on the line when not in use as is indicated to the right of Fig. 5 whereby they will always be readily accessible for use.

While I have disclosed my invention in accordance with a single specific structural embodiment

thereof, such is to be considered as illustrative only, and not restrictive, the scope of the invention being defined in the sub-joined claim.

What I claim and desire to secure by U. S. Letters Patent is:

A line carried wire clothespin comprising a single length of wire bent into a generally circular closed body portion intermediate its ends, the end portions being twisted together at spaced points along the circular body forming relatively short lengths of the strand juxtaposed axially of the circular body and intermediate the twists, said end portions providing a pair of spring arms,

one at each opposite axial side of the generally circular body portion and co-operating therewith to provide line and laundry gripping jaws at opposite sides of a diameter of the body portion.
